(57) **CLAIM**

The ornamental design for a dryer vent, as shown and described.

DESCRIPTION

FIG. 1 is a top, front and left perspective view of a dryer vent showing my new design;

FIG. 2 is a front elevational view thereof;

FIG. 3 is a rear elevational view thereof;

FIG. 4 is a right view thereof;

FIG. 5 is a left view thereof;

FIG. 6 is a top plan view thereof;

FIG. 7 is a bottom plan view thereof; and,

FIG. 8 is a bottom, rear and right perspective view thereof. The broken lines depict portions of the dryer vent that form no part of the claimed design.

1 Claim, 8 Drawing Sheets(56)
